VANITY CASE AND ANALOGOUS ARTICLE

David H. Zell, Brooklyn, N. Y.

Application June 25, 1934, Serial No. 732,213

11 Claims. (Cl. 132—83)

This invention relates to vanity cases and analogous articles, and has for its general object and purpose to provide an article of this character, of novel and durable construction, which will be 5 convenient and serviceable in practical use.

A more particular object is to provide an improved construction of the case body, having means cooperating with parts of a cosmetic holding tray to quickly, accurately and securely position said tray in properly assembled relation with the case body.

Another object is to provide a door or closure for the open side of the case body, hingedly mounted on one end of the tray, and a simple 15 and efficient device mounted in the opposite end of the case body for releasably latching the door in its closed position.

A further object of the invention resides in the provision of a transversely extending compartment at one end of the case body to receive a lipstick holder having one of its ends shaped to conform to the contour of the case, and means coacting with said holder to prevent casual outward movement thereof through the open end of the 25 compartment.

With the above and other objects in view the invention consists in the improved vanity case or analogous article and in the form, construction and relative arrangement of its several parts, as 30 will hereinafter be more fully described, illustrated in the accompanying drawing and subsequently incorporated in the subjoined claims.

In the drawing wherein I have illustrated one simple and practical embodiment of my present improvements, and in which similar reference characters designate corresponding parts throughout the several views,

Figure 1 is a perspective view, illustrating a preferred form of the device and showing the 40 case open.

Fig. 2 is a top plan view, certain parts being shown in section.

Fig. 3 is a longitudinal sectional view taken on the line 3—3 of Fig. 1.

Fig. 4 is a similar sectional view taken on the line 4—4 of Fig. 2.

Fig. 5 is a transverse section taken on the line 5—5 of Fig. 1.

Fig. 6 is a transverse section taken on the line 50 6—6 of Fig. 2.

Fig. 7 is a fragmentary horizontal section taken on the line 7—7 of Fig. 3.

Fig. 8 is a detail perspective view of the door latch member.

55 Referring in detail to the drawing, the body of

the case includes a sheet metal plate forming the rear or bottom wall 5 and opposite longitudinal edge walls 6 of V-shaped cross-sectional form. The free upper edges of the latter walls are horizontally extended inwardly and then turned outwardly, as at 7, and tightly clinched upon the edges of a sheet of decorative material 8 which covers the outer surfaces of said bottom and edge walls. 5

The end members 9 of the case body are also of V-shaped cross-sectional form. Each of these end members has opposite end portions of triangular shape and at the open side of said member the walls thereof are horizontally extended, as at 10, to telescopically receive one end of the bottom 15 and edge walls 5 and 6 of the case body. The end members may be welded or mechanically secured to said body walls in any approved manner. 10

Adjacent one end of the bottom wall 5 lugs 11 are struck upwardly therefrom, and similar lugs 20 12 are provided near the opposite end of said wall but preferably disposed at right angles to the lugs 11. Additional lugs 13 are provided adjacent to the side edges of said bottom wall. 25 These lugs serve to properly position and hold a cosmetic containing tray within the case body.

30 The tray includes a bottom section 14 and a top section 15 of dish-shaped form, hinged to the bottom section at one side thereof, as at 16. The side walls of the tray section 14 are outwardly offset to provide upstanding flanges 17, 35 which yield upon insertion of the tray and snap under the edges 7 of the walls 6 of the case body, as clearly shown in Figs. 5 and 6 of the drawing. One end wall of the tray section 14 is also outwardly offset and provided at its upper edge with a laterally projecting flange 18 which underlies the upper edge portion 10 of one of the end members 9. In this manner the tray is securely held in its assembled position against shifting movement with respect to the case body. 40

One side wall of the tray section 14 is provided with an opening to accommodate a spring held latch member 19 which coacts with a flange 20 on the tray section 15 to hold the latter in closed 45 superposed relation to the tray section 14. The main tray section 14 is adapted to contain face powder while the section 15 may contain rouge and other cosmetics.

Upon one end of the tray section 14 the door 50 or closure member 21 is mounted by means of a spring hinge of conventional form, indicated at 22. This door is provided on its inner side with the usual mirror 23, and at its free end the door frame is formed with an apertured lug 24. Move- 55

ment of the door to open position under the action of the spring hinge is limited by abutting contact of the door with the edge 10 of one of the ends 9 of the case body. When closed, the outer surface of the door is flush with the surfaces of the parts 7 and 10 of the case body.

The door is securely held in its closed position by the novel latching device shown in Figs. 7 and 8 of the drawing. Referring thereto, it will be seen that this device consists of a strip of spring steel 25, having a central bowed section 26 provided with an upstanding keeper 27. This keeper has a laterally offset lip 28 struck therefrom. The strip 25 near its opposite ends is twisted to provide the finger pieces 29 disposed at right angles to the remaining portion of the strip, and projecting outwardly through openings 30 in the end walls of one of the members 9. As shown in Fig. 4 the bowed section of the strip 25 extends under the offset end wall of the tray section 14 and the keeper 27 projects upwardly through the opening 31 therein.

When the door 21 is closed the lug 24 enters between the upwardly extending offset part of the end wall of tray section 14 and the keeper 27, striking the lip 28 of the latter and displacing the keeper against the resistance of the spring strip 25. When the door is fully closed the keeper returns to normal position and lip 28 thereof enters the aperture of lug 24 to closely coact with the lower edge of said aperture. Accidental pressure against either one of the finger pieces is ineffective to operate the latch and release the door, as the latch strip would merely be shifted bodily in the direction of its length. It is necessary to simultaneously press both finger pieces inwardly. This causes the bowed central section of the latch strip to yield, thus laterally displacing the keeper 27 from its normal position to disengage the lip 28 from lug 24. Thereupon the spring hinge 22 moves the door to its open position. It will be seen that there is no positive connection of any kind between the latch device and the case body thus simplifying assemblage of the parts. Also the latch operating means is inconspicuous and has a minimum projection from the body walls of the case so that the ornamental symmetry of the latter is not seriously affected.

The above described latch device is not claimed herein as it forms the subject-matter of a divisional application for patent, filed September 28, 1934, Serial No. 745,919.

The hollow member 9 at the other end of the case provides a transverse compartment to receive a lip stick holder 32, one end of said member being cut away to provide an opening therethrough for the insertion of said holder, as clearly seen in Fig. 2 of the drawing. One end of the holder is formed with an enlarged head having a surface contour corresponding to the opposite end of the member 9. The adjacent end of the body plate forming the wall 5 is provided with an upstanding flange, as at 33, said flange being longitudinally split and having its upper portion formed into a spring 34 for frictional bearing contact against the holder 32 to prevent casual outward displacement thereof with respect to the member 9. Thus the symmetrical contour of the case is preserved while the lip stick is easily accessible for use when desired.

From the foregoing description considered in connection with the accompanying drawing, the construction and several advantages of my improved vanity case will be readily understood.

The various parts thereof are of simple form and may be produced and assembled at comparatively small cost. The facing sheet 8 for the case body may be of celluloid, leather or other suitable material, and, if desired, the door 21 may be provided with a similar facing sheet. Insofar as the novel mechanical features of my present invention are concerned it will be understood that the cross sectional shape or contour of the case body may be varied as desired. Also the detail features of the present disclosure are susceptible of more or less modification or change, and I therefore reserve the privilege of resorting to all such legitimate alternative structural variations thereof as may be fairly considered within the spirit and scope of the appended claims.

I claim:

1. A case of the character described comprising a body open on one side, a container, said body having spaced means adapted to coact with the container when inserted through the open side of the case to position said container relative to the body walls, and said container including yieldable marginal walls underlying certain of the case body walls at the edges thereof. 20

2. A case of the character described comprising a body open on one side, a container, said body having a bottom wall provided with spaced upwardly projecting lugs to coact with the container when inserted through the open side of the case to position said container relative to the body walls, and said container including yieldable marginal walls underlying certain of the case body walls at the edges thereof. 30

3. A case of the character described comprising a body open on one side, a container, said body having spaced means adapted to coact with the container when inserted through the open side of the case to position said container relative to the body walls, and said container including longitudinal side walls, outwardly offset to provide upstanding yieldable flanges, adapted to be inwardly compressed upon insertion of the container and resuming a normal position in underlying relation to opposite edges of the case body walls. 40

4. In a case of the character described, a sheet metal member embodying the bottom and opposite longitudinal side walls of the case, separate hollow sheet metal end members having edge portions telescoped upon and secured to the ends of said bottom and side walls, corresponding edges of said side walls and end members defining an opening through one side of the case, 50 and the case structure having spaced integral parts thereof adapted to coact with exterior surfaces of a container inserted within the case through said opening, to position the container therein and hold the same against shifting movement relative to the case walls. 55

5. In a case of the character described, a sheet metal member embodying the bottom and opposite longitudinal side walls of the case, separate hollow sheet metal end members having edge portions telescoped upon and secured to the ends of said bottom and side walls, one of said latter members having an opening through one end thereof, a lip stick holder insertable through said opening and having a head at one of its 65 ends corresponding in contour with the opposite end of said member, and yieldable means to engage and releasably retain the lip stick holder within said end member. 70

6. In a case of the character described, a sheet

metal member embodying bottom and opposite longitudinal side walls of the case, separate hollow sheet metal end members having edge portions telescoped upon and secured to the ends of 5 said bottom and side walls, one of said latter members having an opening through one end thereof, a lip stick holder insertable through said opening and having a head at one of its ends corresponding in contour with the opposite end 10 of said member, said bottom wall of the case having an upstanding flange at one end thereof, said flange being longitudinally split and the upper portion thereof formed to provide a spring yieldably engaging the lip stick holder to retain 15 the same within said end member.

7. A case of the character described comprising a body having a rectangular opening in one side thereof, a container insertable through said open side of the case body, and said container 20 and the case body having cooperating means including parts longitudinally co-extensive with the body opening and automatically coacting upon insertion of the container to retain the container in a definitely fixed position relative to 25 the walls of the case body.

8. A case of the character described comprising a body open on one side, a container insertable through said open side of the case body, means projecting from one wall of the case body 30 to position the container therein against longitudinal or transverse movement, and said container having means automatically coacting with the body walls of the case at the open side thereof, upon insertion of said container, to prevent 35 outward displacement of the container through the open side of the case body.

9. A case of the character described comprising a body having a rectangular opening in one side thereof, a container having marginal means longitudinally co-extensive with the container and integral with the container structure, coacting with the wall of the case body along opposite 5 side edges of said opening upon insertion of the container therein to prevent outward displacement of the container through the open side of the case body. 10

10. A case of the character described comprising a body having a rectangular opening in one side thereof, a container having marginal means, integral with the container structure, coacting with the wall of the case body along opposite 15 side edges of said opening upon insertion of the container therein to prevent outward displacement of the container through the open side of the case body, and means fixed with relation to the case body, engaging external surfaces of 20 the container walls, to position said container against longitudinal or transverse movement relative to the case body. 25

11. A case of the character described comprising a body having a rectangular opening in one side wall thereof, a container insertable through said opening, said side wall of the casing at opposite edges of the opening, and corresponding marginal walls of the container having coacting parts, longitudinally co-extensive with said edges of the 30 opening, to prevent outward displacement of the container therethrough. 35
